ABSTRACT

A footwear storage and display rack includes a mounting member configured to be mounted to a wall or other generally vertical surface. The mounting member includes an upper portion and a lower portion. A footwear shelf includes a proximal section and a distal section with the proximal section extending from the lower portion of the mounting member so as to be configured at an angle between about 0 degrees and about 90 degrees with respect to the wall or other generally vertical surface when the mounting member is secured to the wall or other generally vertical surface. The distal section extends from the proximal section. An accessory support extends from the upper portion of the mounting member.

FOOTWEAR STORAGE AND DISPLAY
RACK

CLAIM OF PRIORITY

This application claims the benefit of U.S. Provisional Application No. 62/556,878, filed Sep. 11, 2017, the contents of which are hereby incorporated by reference.

FIELD OF THE INVENTION

The present disclosure relates generally to footwear storage devices and, in particular, to a footwear storage and display rack that also accommodates one or more related accessories.

BACKGROUND

Athletic shoes are often used with additional apparel items or equipment. For example, an individual playing basketball uses a basketball and typically wears basketball shoes. As another example, an individual playing baseball uses a baseball and may wear a baseball cap and baseball shoes. A shoe storage device that also stores associated apparel and/or equipment would make access easier and also reduce the chances that the item of apparel or piece of equipment is lost. In addition, an individual may wish to store the items together for decorative display purposes, such as a pair of basketball shoes displayed with a basketball or a pair of baseball shoes displayed with a baseball or cap of the owner's favorite team. Such a storage and display device could find use in a retail environment as well.

SUMMARY

There are several aspects of the present subject matter which may be embodied separately or together in the devices and systems described and claimed below. These aspects may be employed alone or in combination with other aspects of the subject matter described herein, and the description of these aspects together is not intended to preclude the use of these aspects separately or the claiming of such aspects separately or in different combinations as set forth in the claims appended hereto.

In one aspect, a footwear storage and display rack includes a mounting member configured to be mounted to a wall or other generally vertical surface. The mounting member includes an upper portion and a lower portion. A footwear shelf includes a proximal section and a distal section with the proximal section extending from the lower portion of the mounting member so as to be configured at an angle between about 0 degrees and about 90 degrees with respect to the wall or other generally vertical surface when the mounting member is secured to the wall or other generally vertical surface. The distal section is movable with respect to the proximal section so that a length of the footwear shelf is adjustable. An accessory support extends from the upper portion of the mounting member.

In another aspect, a footwear storage and display rack includes a mounting member configured to be mounted to a wall or other generally vertical surface. The mounting member includes an upper portion and a lower portion. A footwear shelf includes a proximal section and a distal section with the proximal section extending from the lower portion of the mounting member so as to be configured at an angle between about 0 degrees and about 90 degrees with respect to the wall or other generally vertical surface when

the mounting member is secured to the wall or other generally vertical surface. The distal section extends from the proximal section. An accessory support extends from the upper portion of the mounting member.

5

BRIEF DESCRIPTION OF THE DRAWINGS

- FIG. 1A is a perspective view of the footwear rack of the disclosure with the footwear shelf in a first configuration;
 10 FIG. 1B is a perspective view of the footwear rack of the disclosure with the footwear shelf in a second configuration;
 FIG. 1C is a perspective view of the footwear rack of the disclosure with the footwear shelf in a third configuration;
 FIG. 2 is a side perspective of the footwear rack of FIG. 1A;
 15 FIG. 3 is a front elevational view of the footwear rack of FIG. 1A;
 FIG. 4 is a side end elevational view of the footwear rack of FIG. 1A;
 20 FIG. 5A is a top plan view of an embodiment of the footwear rack of the disclosure holding a pair of shoes and a ball cap;
 FIG. 5B is a front elevational view of the embodiment of the footwear rack of FIG. 5A;
 25 FIG. 5C is a side elevational view of the embodiment of the footwear rack of FIGS. 5A and 5B;
 FIG. 6A is a top plan elevational view of an embodiment of the footwear rack of the disclosure holding a pair of shoes and a basketball;
 30 FIG. 6B is a front elevational view of the embodiment of the footwear rack of FIG. 6A;
 FIG. 6C is a top plan of the embodiment of the footwear rack of FIGS. 6A and 6B.

35

DETAILED DESCRIPTION OF EMBODIMENTS

An embodiment of the footwear storage and display rack of the invention is indicated in general at 10 in FIGS. 1A-4. The rack includes a mounting member 12 that may be mounted to a wall or other generally vertical surface. More specifically, the mounting member 12 may be planar and may include apertures, indicated at 14a and 14b in FIG. 3, that receive fasteners, such as screws or nails, that engage the wall or other surface. Adhesive or other wall fastening arrangements known in the art may be used instead so that the apertures 14a and 14b (FIG. 3) may optionally be omitted. As another alternative, a single aperture and fastener may be used. In addition, the mounting member 12 does not have to be planar, but may instead be another configuration with a surface that is configured to engage the surface of a wall or other support.

An accessory support, indicated in general at 16 in FIG. 1A, extends from an upper portion of the mounting member 12, and is configured to support an item of apparel or piece of sports equipment. As an example only, the accessory support may take the form of a panel 22 that extends from the top portion of the mounting member at an angle (23 in FIG. 4) of approximately 90 degrees so as to be generally horizontal. The accessory support may include a circular opening 24 sized to cradle the lower portion of a ball or the like (as illustrated in FIGS. 6A-6C). A cap may alternatively be placed on the accessory support, as illustrated in FIGS. 5A-5C.

While an opening sized to cradle a basketball is shown at 24 for the accessory support 16, the opening may alternatively be sized to cradle the bottom portion of a baseball. Alternatively, the panel 22 may be provided with several

smaller openings so that a number of baseballs or golf balls may be held. As another alternative, the opening 24 may feature a different shape, or it may be eliminated entirely.

While the accessory support 16 is illustrated as a generally horizontal panel, it may instead take the form of a bracket or any other structure configured to support an accessory or clothing article. Examples include, but are not limited to, pegs to hold one or more caps, a ball holder or a bracket to hold a golf club, pool cue, rifle or fishing pole.

A footwear shelf, indicated in general at 18 in FIGS. 1A-4, extends from a lower portion of the mounting member 12 in a tilted fashion, such as at an angle (26 of FIG. 4) between 0 degrees and 90 degrees with the supporting wall or other surface.

The footwear shelf includes a proximal section 30 and a distal section 32. The distal section is provided with an upturned retaining lip 33. The proximal section 30 is provided with a pair of elongated slots 34a and 34b, while the distal section is provided with a pair of apertures that receive fasteners such as screws 36a and 36b (FIGS. 1A-1C) upon which are mounted nuts 38a and 38b (FIGS. 2 and 4). When the nuts 38a and 38b are loosened, the screws 36a and 36b are free to traverse their corresponding slots so that the distal section 32 may be slid along the proximal section, as illustrated in FIGS. 1A-1C. As a result, the length (indicated at 42 in FIG. 4) of the footwear shelf 18 may be adjusted to accommodate different shoe sizes. When the desired length is selected, the nuts 38a and 38b are tightened to secure or lock the proximal and distal sections of the footwear shelf in the desired configuration. As a result, a pair of shoes, or other footwear item, may be supported on the footwear shelf 18, as illustrated in FIGS. 5A-6C.

As illustrated in the embodiment described above, the mounting member 12, accessory support 16 and the proximal portion 30 of the footwear shelf could be formed from a single metal panel that is cut and bent to form the three portions of the rack 10. They alternatively may be separately formed and then joined together.

It should be noted that the slots could instead be formed in the distal section 32, with the screws 36a and 36b and nuts 38a and 38b mounted in the proximal section. Furthermore, the elongated slots 34a and 34b and screws 36a and 36b (with nuts) may be replaced with a single slot and screw (with nut). In addition, other sliding arrangements known in the art could be used, such as channels on one section receiving the edges or a track on the other section. As another alternative, the sliding arrangement between the proximal and distal sections of the footwear shelf could be replaced with an arrangement where the position of the distal section could be adjusted with respect to the proximal section in a non-continuous fashion, such as with tabs or hooks on one section engaging a series of notches on the other section, to adjust the length of the footwear shelf.

While the preferred embodiments of the disclosure have been shown and described, it will be apparent to those skilled in the art that changes and modifications may be made therein without departing from the spirit of the disclosure, the scope of which is defined by the following claims.

What is claimed is:

1. A footwear storage and display rack comprising:
  - a mounting member configured to be mounted to a wall or other generally vertical surface, said mounting member including an upper portion and a lower portion;
  - b. a footwear shelf including a proximal section and a distal section with the proximal section extending from the lower portion of the mounting member so as to be

configured at an angle between about 0 degrees and about 90 degrees with respect to the wall or other generally vertical surface when the mounting member is secured to the wall or other generally vertical surface, and the distal section movable with respect to the proximal section so that a length of the footwear shelf is adjustable;

c. an accessory support including a panel extending from the upper portion of the mounting member at an angle of approximately 90 degrees with respect to the wall or other generally vertical surface when the mounting member is secured to the wall or other generally vertical surface.

2. The footwear storage and display rack of claim 1 wherein the distal section of the footwear shelf is slidably mounted to the proximal section.

3. The footwear storage and display rack of claim 2 wherein the proximal section of the footwear shelf includes a slot and the distal section includes a fastener configured to traverse the slot.

4. The footwear storage and display rack of claim 3 wherein the fastener includes a screw and a nut.

5. The footwear storage and display rack of claim 1 wherein the distal section of the footwear shelf includes a retaining lip.

6. The footwear storage and display rack of claim 1 wherein the mounting member, accessory support and the proximal section of the footwear shelf are formed from a single plate of material.

7. The footwear storage and display rack of claim 1 further comprising an opening formed in the panel, said opening sized to cradle a sports ball.

8. The footwear storage and display rack of claim 1 wherein the mounting member is planar.

9. A footwear storage and display rack comprising:

- a mounting member configured to be mounted to a wall or other generally vertical surface, said mounting member including an upper portion and a lower portion;
- b. a footwear shelf including a proximal section and a distal section with the proximal section extending from the lower portion of the mounting member so as to be configured at an angle between about 0 degrees and about 90 degrees with respect to the wall or other generally vertical surface when the mounting member is secured to the wall or other generally vertical surface and the distal section extending from the proximal section;
- c. an accessory support extending from the upper portion of the mounting member;
- d. wherein the mounting member, accessory support and the proximal section of the footwear shelf are formed from a single plate of material.

10. The footwear storage and display rack of claim 9 wherein the distal section of the footwear shelf is slidably mounted to the proximal section.

11. The footwear storage and display rack of claim 10 wherein the proximal section of the footwear shelf includes a slot and the distal section includes a fastener configured to traverse the slot.

12. The footwear storage and display rack of claim 11 wherein the fastener includes a screw and a nut.

13. The footwear storage and display rack of claim 9 wherein the distal section of the footwear shelf includes a retaining lip.

14. The footwear storage and display rack of claim 9 wherein the accessory support includes a panel.

15. The footwear storage and display rack of claim 14 wherein the panel extends from the upper portion of the mounting member at an angle of approximately 90 degrees with respect to the wall or other generally vertical surface when the mounting member is secured to the wall or other 5 generally vertical surface.

16. The footwear storage and display rack of claim 15 further comprising an opening formed in the panel, said opening sized to cradle a sports ball.

17. The footwear storage and display rack of claim 14 10 wherein the mounting member is planar and the panel extends from the upper portion of the mounting member at an angle of approximately 90 degrees with respect to the mounting member.
